UNITED STATES PATENT OFFICE.

JOHN G. DUNKER, OF CHICAGO, ILLINOIS, ASSIGNOR TO THE WAHL COMPANY, OF CHICAGO, ILLINOIS, A CORPORATION OF DELAWARE.

CALCULATING MACHINE.

1,274,526.

Specification of Letters Patent.

Patented Aug. 6, 1918.

Application filed September 1, 1916. Serial No. 118,147.

To all whom it may concern:

Be it known that I, JOHN G. DUNKER, a citizen of the United States, residing at Chicago, in the county of Cook and State of Illinois, have invented certain new and useful Improvements in Calculating Machines, of which the following is a specification.

My invention is a totalizer clear signal for computing machines and is especially adapted for use with computing machines in which the totals are copied figure by figure.

One of the objects of my invention is to improve on the totalizer clear signals of the prior art both in structure and ease of operation.

Another object of my invention is to provide a totalizer clear signal which is adapted to be used with a typewriter computing machine, and which will give an indication as soon as a wrong digit is printed in any decimal place instead of having to wait until the total has been entirely printed before giving an indication that an error has been made in copying the total exhibited by the totalizer.

Another object of my invention is the provision of a totalizer clear signal which can be shifted from the control of one totalizer to another, and will thus coöperate with either of said totalizers. This feature is especially valuable in the machine on which I have illustrated my invention, viz., the Wahl cross footing machine. Said machine has a plurality of totalizers adapted to compute numbers written in vertical columns. There is also a cross footing totalizer adapted to compute numbers written in a horizontal line. My totalizer clear signal is so constructed that it may be brought into coöperation with any of the vertical totalizers or into coöperation with the cross totalizer as may be desired. These, and other objects of my invention, will be more fully set forth in the following specification and claims.

The invention may be best understood by reference to the following figures of which—

Figure 1 is a front elevation of a Wahl cross footing machine equipped with my invention.

Fig. 2 is a partial section along the lines 2—2 of Fig. 1.

Fig. 3 is a detail of a master wheel and some of the totalizer wheels in section.

Fig. 4 is a perspective view of some of the

parts which are peculiar to my herein disclosed invention. 55

Fig. 5 is a detail of the part of the special key for printing the characteristic mark and its connections.

Fig. 6 is a detail of the typewriter bar, 60 and

Fig. 7 is a detail of a certain part of the mechanism.

Similar characters of reference refer to like parts throughout the several views. 65

Reference to Fig. 1 will disclose a Wahl cross footing machine, and since this machine is well known commercially, it will not be necessary to give an extended description herein. It will be sufficient to say that the carriage of the typewriter is equipped with a traveling truck 10 upon which is mounted a plurality of totalizers 11, 12, 13 and 14. These totalizers are adapted to have numbers inserted in them *seriatim* by a master wheel 15, which is rotated a differential amount upon the operation of any of the numeral keys 16 of the typewriter 17. 75

For the sake of clearness, in Fig. 1 I have shown a typewriter in which the usual alphabetical keys are absent. However, it is to be understood that the Wahl cross footing machine is usually mounted on a typewriter possessing the full equipment of alphabetical keys in addition to the numeral keys necessary to operate the computing attachment. 80

The vertical totalizers 11, 12, 13 and 14 are equipped with means for intermittently picking up the cross totalizer 18 which is mounted on the truck 19 reciprocating in ways 20, rigid with the frame work of the machine. A spring 21 serves to hold the cross totalizer 18 in its normal position, as shown in Fig. 1, and a pick-up beam 22 is attached to the truck 19 and adapted to coöperate with connecting locations (not shown) on the totalizers 11, 12, 13 and 14. 85

The mechanism just described has for its purpose the picking up of the cross totalizer 18 and causing said totalizer to travel with the truck 19 during the time the vertical totalizers 11, 12, 13 and 14 are engaged with the master wheel 15. A cross master wheel 23 serves to insert numbers in the cross totalizer 18 simultaneously with the insertion of these numbers in any of the vertical totalizers, the master wheels 23 and 15 revolv-

100

105

ing equal amounts upon the operation of any of the numeral keys 16.

The vertical totalizers 11, 12 and 14 are provided with cams 24, 25 and 26, which are adapted to contact with a roller 27 on an arm 28, which is connected to a gear shift device which controls the rotation of the master wheel 23. By means of these cams, a definite program of calculation for the cross totalizer 18 may be set up on the truck 10, and thus as numbers are written in horizontal alinement, the direction in which these numbers are entered into the cross totalizer 18 is automatically determined.

15 It will not be necessary to go into a description of the mechanisms by which the above recited results are brought about since said mechanisms are all parts of the Wahl cross footing machine which has been 20 on the market for some time.

I shall start the description of parts peculiar to my invention with the premise that operation of the numeral keys 16 causes a differential rotation of the vertical master wheel 15 and the cross master wheel 23, the rotation of the latter being in a direction determined by the contact of one of the cams 24, 25 and 26 with the roller 27. After the number corresponding to the key depressed has been inserted in the totalizers, the typewriter carriage escapes one step and the master wheels 15 and 23 engage in the next lower decimal place of their associated totalizers. Numbers are inserted in the machine one digit at a time. When it is wished to clear any of the totalizers the numbers shown thereon are subtracted. For instance, if the cross totalizer shows a total of 563, it will be necessary to set the master wheel 23 to subtraction, tabulate to the hundredths position and then operate, in the order named, the 5, 6 and 3 keys. This will result in the subtracting of 563 from the cross totalizer 18, which will then stand at 45 zero. However, it sometimes happens that the operator will incorrectly read the number present in the totalizer and subtract either too much or too little, which results in the totalizer not being clear.

50 It is one of the objects of my invention at the time an error is made immediately to give the operator an indication that an incorrect number has been subtracted from the totalizer, and as will hereinafter be disclosed, this indication is given when the erroneous digit is subtracted. The operator does not have to wait until the entire number has been written out before discovering an error.

60 Describing now the parts peculiar to my invention, reference to Fig. 4 will disclose that the wheels 29 and 30, which may be taken as typical wheels of the cross and vertical totalizers, are made with a key hole shaped notch 31 between two of their teeth.

The notch 31 is so positioned in reference to the number wheels of the totalizer that when the number wheels stand at 0, this notch is opposite a knob 32 on a bar 33 (Figs. 1 and 4) slidably mounted on a plate 34 of 70 the framework of the machine. Two screws 35 and 36 which go through elongated slots 37 and 38 in the bar 33 serve to maintain said bar in its proper position in respect to the plate 34. The position of the bar 33 is 75 controlled by the lever 39 pivoted to the plate 34 at 40, and having a nose 41 which engages a slot 42 in the lower end of the bar 33, and a downwardly extending arm 43 which is adapted to contact with a lever 44 80 on a shaft 45 which is rotatably and slidably mounted in the framework supporting the cross totalizer. A spring 46 extending between the arm 43 and a stud on plate 34 serves to hold said arm, and with it the bar 33, in the position, as shown in Fig. 4. The actuator for the vertical totalizers is equipped with a similar bar 47 having a knob 48 adapted to engage with key-hole notches 31 in the wheels of the vertical totalizers, said bar 47 being maintained in its depressed position by an arm 49 of a bell crank pivoted to a plate of the framework at 53, and held in a normal position by a spring 51, said arm 49 engaging in a slot 50 in the bottom of the bar 47.

Leaving for a moment the action of the bar 47 and returning to consideration of the bar 33 which co-operates with the cross totalizer, reference to Fig. 4 will disclose that the shaft 45 which, it will be remembered, is both rotatably and slidably mounted in the framework, has rigidly attached to it an arm 52, which has an ear 54 co-operating with notches 55 and 56 in an escutcheon 100 plate 57. Loosely mounted on the shaft 45 between the collars 58 and 59 rigid on said shaft is a handle 60 to which is attached a pointer 61, having an ear 62 thereon to embrace the escutcheon plate 57. On the arm 105 52 is pivoted at 66 a detent 63 held in contact with a latch plate 64 by a spring 65 extending from said detent to an extension 67 on the arm 52 (Fig. 5). The arm 52 also contains a slot 68 in which is a pull rod 69 110 extending to a special key lever 70 of the typewriter. This special key lever has attached to it a type bar (Fig. 6) which prints a star or other characteristic mark.

I will now describe the process of printing 115 out the total from the cross totalizer 18. By means of the vertical carriage, the cross carriage is brought to a position, as shown in Fig. 3, in which the cross totalizer wheels 29 are to the right of the cross master wheel 23. The type lever 70 is then depressed by means of a key 71, this resulting in the printing of the characteristic mark or star on the work sheet, and by means of the rotation of the arm 52, the consequent rotation of the shaft 120 125 130

45 which results in elevating the bar 33 into a position where the knob 32 will be in line and adapted to enter the key hole shaped notches 31 in the gear wheels 29 of the cross 5 totalizer. The detent 63, by engaging with the underside of the latch plate 64, will serve to maintain the bar 33 in its raised position. The typewriter carriage will then be tabulated, or spaced step by step, to the 10 highest significant figure appearing in the cross totalizer 18. Since, by hypothesis, all the wheels of the totalizer to the left of the said highest wheel stand at 0, the notches 31 of said wheels will be in line and this fact 15 will permit the passage of the totalizer over the knob 32 and said knob through key hole notches 31. When the highest significant digit is printed out, the notch in the wheel 29 in that decimal place will be brought into 20 line with said knob 32, and further escape- 25 ment of the typewriter carriage is permitted. This process will continue until the entire number present in the totalizer has been printed out, in which event the knob 32 will 30 be engaged in the wheel 29 in the lowest decimal place of the totalizer, and the truck 19 will be permitted to return to its normal position without interference when the same shall have been unlatched from the 35 vertical truck 10. Assume, however, that during the printing of this total one of the wheels 29 was not returned to 0. Further spacing of the typewriter carriage would then be prevented by reason of the fact that 40 the notch 31 was not in alinement with the knob 32. This would at once call the attention of the operator to the fact that an error had been made in the particular decimal place operated in. Such an error would be 45 corrected by reversing the direction of rotation of the master wheel 23 and inserting the erroneous number, and then throwing the machine again into subtraction and printing out the correct number. It will thus be seen that the procedure of clearing out the cross totalizer is as follows:

The characteristic mark is first printed, then the totalizer tabulated, or spaced step by step, to the highest significant digit and 50 the number in said totalizer printed out digit by digit. In case this is correctly done the machine will function in the usual manner. In case, however, an error is made in the printing out of the digit from any decimal place, spacing of the typewriter carriage will be prevented and the fact of the machine being tied up will direct the attention of the operator to the error.

Considering now the operation of the device upon the vertical totalizers, reference to 60 Fig. 4 discloses that rotatably mounted on the shaft 45 is an arm 72 which is held in its position by an ear 73 (Fig. 7) attached to the framework in any suitable manner.

65 Mounted on the arm 72 is a pin 85, which is

adapted to enter a hole 74 in the arm 52 when the shaft 45 is shifted so that the pointer 61 is under the V in the escutcheon plate 57. When in this position the ear 54 will register with the notch 56 and operation of the special key 71 will, therefore, 70 rotate the arm 72, which is connected by a link 75 to an arm 76 rigid on a jack shaft 77 rotatably mounted in the framework. On said shaft 77 is rigidly mounted an arm 78, 75 which serves to operate a depending arm 79 of the bell crank formed with arm 49. When it is desired to extract the total from one of the vertical totalizers, the handle 60 is shifted so that the pointer 61 is below the 80 V on the plate 57, and when in this position, operation of the special key 71 will raise not the bar 33 of the cross totalizer but the bar 47 which is adapted to engage the vertical totalizer. These vertical totalizers may 85 then be cleared as described in connection with the cross totalizer 18 and an error in extracting the proper number from any of the decimal places of said vertical totalizer will at once, by preventing the spacing of 90 the typewriter carriage, give the operator a warning that the mistake has been made.

The knobs 32 and 48 of each bar 33 and 47 are larger in diameter than the width of opening leading from the root of the teeth 95 to the notch 31 of the wheels 29 and 30, such construction making it necessary that the totalizer to be cleared is to the right of the master wheel when the key 71 is depressed.

In Fig. 2 I have shown a vertical totalizer partly in section, and it will be observed that the particular wheel 30 shown in said section has in it three notches 31, these notches being spaced at a distance of 10 105 teeth apart, each notch corresponding to the 0 position of the numeral wheel 80 in the same decimal places as the wheel 30.

The elongated notch 68 in the arm 52 is for the purpose of allowing the key 71 to 110 return to its normal position while the arm 52 remains latched down by the detent 63. After a total has been printed out, the detent 63 is, of course, unlatched by means of the finger piece 81 and the parts returned to 115 their normal position under the influence of the spring 46 or the spring 51 according as the total clearing device has been used with the cross or vertical totalizer.

Another mode of operating the device 120 would be to depress the arm 52 by means of the finger piece 81 without operating the special key 71. The totalizer would then be tabulated to the space before the first significant figure, this tabulation being permitted 125 on account of the alinement with the key hole shaped notches. The special key would then be operated, which would print the star, and the carriage would space one space, thus bringing the wheel in the decimal place 130

of the first significant figure in a position to be operated on by the master wheel. The total would then be printed out digit by digit, and the notches 31 brought into alignment. The procedure just described would obviate the necessity of a space between the characteristic mark and the highest significant figure of the total printed out.

- Many advantages result from my improved device herein described. In all the devices of the prior art with which I am acquainted the indication that the totalizer has not been cleared was not given until the operator had entirely printed out the total in the totalizer and attempted to print the characteristic mark usually employed as an indication that the totalizer is clear. In my device, the characteristic mark is printed first and then failure to properly clear any decimal places of the totalizer results in the tying up of the machine. The operator is at once notified of the error and must correct it immediately without having to wait until the entire number has been printed.
- 25 I do not wish to restrict myself to the precise structure herein disclosed, since many modifications may be made therefrom without departing from the spirit of my invention, since I claim:
- 30 1. In a calculating machine, the combination of a totalizer gear wheel, a key hole slot in said gear wheel, thereby determining the zero position of said wheel, and a plunger having an enlarged end to enter said slot, and means to bring said plunger in contact with said wheel and thereby mechanically determine whether or not said wheel is in its zero position.
2. In a calculating machine, the combination of a totalizer, a set of numeral wheels having key hole slots in them to thereby determine the zero position of said wheels, a plunger having a head adapted to enter said slots, and means to bring said plunger in a position to engage said slot and afterward contact with said wheels *seriatim*.
3. In a calculating machine, the combination of a totalizer, a wheel having a key hole slot therein to thereby determine a zero position, a plunger slidably mounted on the framework of the machine, said wheel and plunger being relatively movable to each other, and means to elevate said plunger into the path of said wheel.
- 55 4. In a calculating machine, the combination of a set of totalizer wheels having a configuration peculiar to the zero position thereof, a zero determining device adapted to coopearte with said wheels, means for printing a characteristic mark, and means connecting said printing means and said zero determining means and adapted to bring said zero determining means in coöperation with said totalizer.
- 60 5. In a calculating machine, the combina-

tion of a set of totalizer wheels having a configuration peculiar to the zero poition thereof, a zero determining device adapted to contact with said totalizer wheels *seriatim*, means for printing a characteristic mark, 70 and means connecting said printing means and said zero determining means and adapted to bring said zero determining means in coöperation with said totalizer.

6. In a calculating machine, the combination of a totalizer having a set of gear wheels, a second totalizer also having a set of gear wheels, a zero determining device adapted to contact *seriatim* with said first totalizer, a second zero determining device 80 adapted to contact *seriatim* with the wheels of said second totalizer and manually operated means to determine which of said zero determining devices shall be brought into co-operation with its respective totalizer. 85

7. In a calculating machine, the combination of a totalizer, a set of wheels therein, a zero determining device adapted to be brought in contact with said wheels *seriatim*, a second totalizer, a series of wheels therein, 90 a second zero determining device adapted to be brought in contact with said wheels *seriatim*, and means for printing a characteristic mark and simultaneously bringing one or the other of said zero determining devices in contact with its respective totalizer. 95

8. In a calculating machine, the combination of a totalizer, a set of wheels therein, a zero determining device adapted to be brought in contact with said wheels *seriatim*, a second totalizer, a series of wheels therein, 100 a second zero determining device adapted to be brought in contact with said wheels *seriatim*, means for printing a characteristic mark and bringing one or the other of said zero determining devices in connection with its respective totalizer, and means for determining which zero determining device shall be operated by said printing means. 105

9. In a calculating machine, the combination of a totalizer including a set of wheels, a zero determining device adapted to be brought in contact with said wheels *seriatim*, a second totalizer, a series of wheels therein, 110 a second zero determining device adapted to be brought in contact with said wheels *seriatim*, and means for printing a characteristic mark and bringing one or the other of said zero determining devices in contact with its respective totalizer. 115

10. In a calculating machine, the combination of a decimal carriage, a totalizer, and a zero determining device adapted to be brought into coöperation with said totalizer, the arrangement of the totalizer and zero 120 determining device being such that motion of said decimal carriage will be prevented unless said totalizer stands at zero during the time said zero determining device is in coöperation with said totalizer. 125

130

11. In a calculating machine, the combination of a decimal carriage, means to advance said decimal carriage in a letter feeding direction, a totalizer, a zero determining device, means to bring said zero determining device into coöperation with said totalizer, and means to prevent the motion of said decimal carriage in a letter feeding direction during the time said zero determining device is connected to said totalizer.
12. In a calculating machine, the combination of a totalizer, a set of members having slots therein, a plunger adapted to be brought into coöperation with said members, and means to advance said members in one direction relative to said plunger, the arrangement being such that advancing means will be inoperative unless said slots are in alinement with said plunger.
13. In a calculating machine, the combination of a totalizer including a set of wheels, a zero determining device adapted to be brought into coöperation with said wheels *seriatim*, a second totalizer, a second series of wheels therein, a second zero determining device adapted to be brought into coöperation with said second set of wheels *seriatim*, means for printing a characteristic mark, a common operating means for actuating said printing means and bringing one or the other of said zero determining devices in coöperation with its respective totalizer, means for determining which zero determining device shall be operated by said printing means, and means for preventing the operation of said printing means unless said determining means is in either of its alternate positions.

In witness whereof, I have hereunto subscribed my name.

JOHN G. DUNKER.
